UNITED STATES PATENT OFFICE.

HARRY H. MARRIOTT, OF KANSAS CITY, MISSOURI.

SIGN.

1,377,904.

Specification of Letters Patent. Patented May 10, 1921.

Application filed February 16, 1920. Serial No. 359,066.

To all whom it may concern:

Be it known that I, HARRY H. MARRIOTT, a citizen of the United States, residing at Kansas City, in the county of Jackson and 5 State of Missouri, have invented a new and useful Sign, of which the following is a specification.

By way of explanation it may be stated that a sign, the letters or characters of which 10 are fashioned from metal foil, and particularly from gold foil, is a peculiarly attractive and effective sign in the daylight. Such a sign, as ordinarily constructed, however, loses practically all of its efficiency and 15 utility after nightfall, because metal foil is opaque, or, at least, so nearly opaque, that the sign cannot be illuminated from the rear after dark.

The foregoing being understood, it may 20 be stated that it is the object of this invention to provide a sign which, in the daytime, will possess all of the advantages of a foil sign, and, as well, be capable of illumination after nightfall.

25 It is within the province of the disclosure to improve generally and to enhance the utility of devices of that sort to which the invention appertains.

With the above and other objects in view, 30 which will appear as the description proceeds, the invention resides in the combination and arrangement of parts and in the details of construction hereinafter described and claimed, it being understood that, within 35 the scope of what is claimed, changes in the precise embodiment of the invention shown can be made without departing from the spirit of the invention.

In the accompanying drawings:— 40 Figure 1 shows in front elevation, a device constructed in accordance with the invention, parts being broken away; Fig. 2 is a section taken approximately on the line 2—2 of Fig. 1; and Fig. 3 is an elevation 45 showing the netting and the foil carried thereby.

In carrying out the invention there is 50 provided a panel which is a composite structure. The panel includes a front plate 1, which may be made of glass, if desired, paint 2 or the like being applied to the plate 1, so as to render the plate opaque or nearly so.

Portions of the paint 2 are removed or omitted, so as to define openings 3 which may form the letters of a sign, an ornamental design, or any other character which properly forms part of a sign.

To the rear of plate 1, a netting 4 is disposed, the netting 4 preferably being in contact with the plate 1. The netting 4 may be 60 held upon the plate 1 by an edge binder 5 or in any other suitable way.

Pieces of metal foil, preferably gold foil indicated at 6, are secured to the netting 4, the pieces of foil being ordinarily disposed 65 against the front plate 1. The pieces of foil 6 are disposed closely enough together so that the space within the opening 3 will present the characteristic color of the foil 6 in the daytime, the pieces of foil being spaced 70 sufficiently to permit the passage of artificial light therebetween, when the panel is illuminated from the rear.

Ordinarily, the panel is mounted in any suitable way, in the front of a box 7, and is 75 illuminated from the rear by means of one or more lamps 8. Preferably, the netting 4 is gilded or otherwise colored to correspond with the color of the pieces 6 of foil. The entire netting 4 need not be provided with 80 the pieces 6 of foil, neither need the entire netting be gilded or colored otherwise to correspond with the color of the foil, it being obvious that only so much of the netting as is disclosed through the openings 3, need be 85 treated as above alluded to.

The sign forming the subject matter of this application is so constituted that, in the daytime, it will present the attractive features of a gold foil letter, and, it is to be 90 observed, the sign may be illuminated adequately after nightfall.

Having thus described the invention, what is claimed is:—

1. In a device of the class described, a 95 panel comprising a front plate, a netting behind the front plate, and pieces of metal foil secured to the netting, the front plate having a sign-forming opening through which the foil is visible, the pieces of foil 100 being disposed closely enough together so that the space within the opening will present the characteristic color of the foil in daylight, the pieces of foil being separated

sufficiently to permit the passage of artificial light therebetween from the rear; and means for illuminating the panel from the rear.

2. A device of the class described, constructed as set forth in claim 1 and further characterized by the fact that the netting is colored to correspond with the color of the foil.

In testimony that I claim the foregoing as my own, I have hereto affixed my signature in the presence of two witnesses.

HARRY H. MARRIOTT.
